UNITED STATES PATENT OFFICE.

EUGENE E. BARTON, OF CAGAYAN; PHILIPPINE ISLANDS.

MACHINE FOR TREATING MANILA HEMP.

No. 852,410.

Specification of Letters Patent.

Patented May 7, 1907.

Application filed June 6, 1906. Serial No. 264,029.

To all whom it may concern:

Be it known that I, EUGENE E. BARTON, a citizen of the United States, at present residing in the Philippine Islands, at Cagayan de Misamis, and whose post-office address is care of D. L. Barton, 804 H street northwest, Washington, District of Columbia, have invented a new and useful Improvement in Machines for Treating Manila Hemp, of which the following is a specification.

This invention relates to a machine for treating hemp and is especially designed for separating the fiber from the pulp or other undesirable parts of the Manila hemp or abaca plant.

The object of the invention is a device which will automatically bear upon the strip of hemp drawn through the machine and which will strip or separate the fiber from the pulp.

The invention consists of a suitable block, and a pivoted frame having a dull blade adapted to be forced toward the block when a strip of hemp is drawn between the blade and block.

The invention also consists of the novel features hereinafter set forth, pointed out in the claims and shown in the accompanying drawings, in which:—

Figure 1 is a perspective view of the machine. Fig. 2 is a transverse section, the path of the hemp strip being shown in dotted lines, and the pivoted frame being shown in full lines when in use and in dotted lines when not in use. Fig. 3 is a detail perspective view of the blade carrying the frame detached from the machine.

In these drawings, A represents a suitable work table or bench upon which is mounted an upright standard B, having a tapering arm B', extending laterally therefrom and substantially parallel with the front edge of the table. The smaller end of the arm B' is curved downwardly as shown at B² and is then bent back upon itself forming a shaft B³ below the arm B' and parallel to a table A. A rectangular frame is formed of side members C, the said members being metal bars flanged at one end and perforated as shown at C' adjacent the flanged end. To the flanges is connected a dull blade or block D and the opposite ends of the bars C are connected by a rotatable roller F. The frame composed of the bars C, blade D and roller F is pivotally hung or mounted upon the shaft B³, the said shaft passing loosely

through the perforations C' in the bars C. A block of wood E, is placed upon the table A below and parallel to the shaft B³ and has a projecting portion E' extending beyond the end of the shaft, which projecting portion has an upwardly inclined surface, the object of which will be stated hereafter. To the rear of the standard B is arranged an upright bracket G bifurcated at its upper end and in which is journaled a shaft H having mounted therein a pulley H', and a roller H², the said roller extending above and substantially parallel to the roller F.

The operation of the device is as follows: The strip of hemp plant is inserted between the blade D and the block E, and this operation is facilitated by the tapering or inclination of the portion E' of the block which permits the ready insertion of the strip between the blade and the horizontal portion of the block. Normally, the frame, of which the blade D is a member, rests in the position shown in dotted lines in Fig. 2 by reason of the greater weight of the roller over the blade D, and the increased leverage obtain by said roller by reason of its distance from the pivotal points of the bar C. After the hemp strip has been inserted in position between the blade D and the block E, the end is carried upwardly over the rollers F and H² and then forwardly across the tapering arm B'. The hemp is then pulled taut and as it will bear upwardly upon the under side of the roller F, the roller end of the frame, will be lifted into the position shown in Fig. 2 and the blade will be forced downwardly into engagement with the hemp. A strip of hemp plant is then drawn through the device, the pressure of the blade C upon the same preventing all parts of the plant except the fiber, from passing between the blade and the block E, and the fiber will thus be stripped free from the pulp. Power is applied to the pulley H' by means of a belt from any desired source of power and the roller H² rotated in the same direction as the direction of the pulley upon the hemp plant will aid, through friction, to draw the hemp strip between the blade and block.

It will be obvious that a stop of any desired kind can be placed on the table to limit the downward movement of the roller F and also that the lower edge of the block D which I have shown smooth, may be roughened or slightly serrated when desired.

Having thus fully described my invention,

what I claim as new and desire to secure by Letters Patent, is:-

1. A device of the kind described comprising a block, a shaft above the block, a frame having its side members pivotally mounted upon the shaft, a blade forming the front member of the frame, and a rotatable roller forming the rear member of said frame.
2. A device of the kind described comprising a pivoted frame, having a blade at one end and a roller at the rear end, said frame being pivoted adjacent the blade, a rotatable roller arranged above the roller carried by the frame, and a block arranged below the blade.
3. A device of the kind described comprising a block, having one end portion upwardly inclined, a rectangular frame comprising side members, a blade forming the front end members and a rotatable roller forming the rear

member, said frame being pivoted above the block, intermediate the blade and roller, a rotatable roller placed above the frame, and means for rotating the last mentioned roller.

4. A device of the kind described comprising a pivoted frame, having a blade at one end and a rotatable roller at the opposite end, said frame being pivotally mounted between its ends and adjacent the blade, the block arranged below the blade, a bracket arranged adjacent the frame, a shaft carried by said bracket and above and parallel to the roller carried by the frame, the pulley on the shaft, and a roller carried by the shaft, said roller being above and parallel to the roller carried by the frame.

EUGENE E. BARTON.
